RAILROAD TORPEDO SETTER

Lawrence T. Kirk, Abbeville, S. C.

Application February 19, 1944, Serial No. 523,153

5 Claims. (Cl. 246—216)

This invention relates to a torpedo placer and it is one object of the invention to provide a device of this character by use of which a torpedo used as a signal upon railway tracks may be applied to a rail and firmly secured thereon from a moving train or while standing upon the track.

Another object of the invention is to provide a torpedo placer having an elongated handle provided with a hand grip at its upper end and at its lower end provided with means for releasably holding a torpedo in such manner that by thrusting the handle downwardly into engagement with the tread of a rail the torpedo may be quickly applied in firm gripping engagement with the rail.

Another object of the invention is to provide a torpedo placer having jaws at the lower end of its handle so mounted that as the device is thrust downwardly into engagement with the rail the jaws will be moved to bend the strap of the torpedo into gripping engagement with opposite side portions of the head of the rail.

Another object of the invention is to provide the device with levers engaged with ends of a spring serving to normally hold the levers in a retracted position but permitting the levers to be swung outwardly to act upon arms of the jaws and move the jaws downwardly and inwardly to apply the torpedo to the rail.

Another object of the invention is to provide the device with spring fingers so mounted that they may have gripping engagement with opposite sides of the torpedo and firmly, but releasably, hold the torpedo in place within a yoke to which the jaws are pivotally mounted, the spring fingers preventing accidental displacement of the torpedo but allowing displacement of the torpedo from the device after end portions of its strap have been bent into engagement with the rail.

Another object of the invention is to provide a device of this character having a guide for straddling a rail and directing movement thereof towards the rail while applying a torpedo to the rail.

The invention is illustrated in the accompanying drawings wherein:

Figure 1 is a view in elevation looking at the front of the improved torpedo placer.

Figure 2 is a side elevation thereof.

Figure 3 is a view looking at the lower end of the torpedo placer.

Figure 4 is a fragmentary sectional view taken along the line 4—4 of Figure 1.

Figure 5 is a view showing the lower portion of

the torpedo placer principally in vertical section and partially in elevation.

Figure 6 is a perspective view of one jaw of the device.

5 Figure 7 is a view of a torpedo to be applied to a rail by means of the improved placer.

This improved torpedo placer has a handle 1 which may be formed of wood or other suitable material and is of such length that a member of 10 a train crew can easily reach a rail R of a track along which a train is moving while standing upon the train at the back thereof. A hand grip 2 of the type used upon shovels and similar implements is provided at the upper end of the handle 15 in order that the handle may be held and thrust downwardly while applying a torpedo to a rail. While it has been stated that the torpedo is applied by a person standing upon a moving train it is to be understood that the device may also 20 be used by a person standing upon the track for applying a torpedo at a suitable distance back of a train which has been brought to a stop.

At its lower end the handle 1 carries a plate 3 which projects from opposite sides of the handle 25 and has its end portions rolled to form hinge sleeves 4 to which upper ends of levers 5 are pivotally connected by pins 6. A screw 7 serves to secure the plate 3 against the lower end of the handle and this screw also serves to secure a shield 8 having lips 9 and a spacer plate 10 which is disposed between plates 3 and 8. The jaws 11 are formed from strips of stiff sheet metal and each strip is bent to form a flange 12 at the lower end of the jaw having its lower edge formed with 30 a notch 13 midway its width. Substantially midway its length the strip is crimped to form a hinge member 14 of double thickness carrying a sleeve 15 to receive an end bar of a rectangular yoke 16 and pivotally connect the jaw with the yoke.

40 A notch 17 is formed midway the length of the sleeve 15, the notches 13 and 17 being in such relation to each other that when the torpedo 18 is applied to the yoke its straps 19 may pass through the companion notches and then be bent 45 over the flanges and lower ends of the jaws as shown in Figure 1. Upper portions of the strips from which the jaws are formed constitute arms 20 having inwardly projecting lips or flanges 21 at their upper ends for engaging the levers 5 and 50 limiting pivotal movement of the jaws about the pins 22 which pivotally connect the jaws with the levers. These pins pass through sleeves 23 at lower ends of the levers 5 and also through sleeves 24 formed from tongues struck from the arms, and referring to Figure 6 it will be seen that the

sleeves 24 of each arm are spaced from each other so that hooks 25 at ends of a helical spring 26 may be engaged about the pins 22 and mount the spring between the levers where it will serve to normally hold the levers retracted and the jaws extended as shown in Figure 1 with the lips 21 of their arms 20 bearing against outer faces of the levers. By so forming and mounting the jaws the device may be held in one hand with the handle depending and the jaws uppermost and a torpedo fitted through the yoke and its tongues or straps bent into engagement with the jaws. As the torpedo is thrust through the yoke or frame 16 resilient fingers 27 are sprung into position for their free lower ends to engage in grooves at opposite ends of the torpedo and when the device is turned to the applying position shown in Figures 1 and 2 the torpedo will be well supported and prevented from slipping downwardly through the yoke.

When the device is in use the torpedo is applied to the yoke and its straps engaged with the flanges of lips 12 of the jaws. The handle is grasped by its hand hold or grip 2 and by reaching downwardly from the rear end of a train the person operating the device may thrust it downwardly towards the head or tread of a rail. A guide 28 which is formed of stiff metal is disposed vertically at the front of the handle with its shank 29 secured thereto by screws 30 and its arms or forks 31 extending downwardly in diverging relation to each other and projecting from opposite sides of the handle. The forks are of such length and disposed in such diverging relation to each other that they may straddle the rail to which the torpedo is to be applied as shown in Figure 1. The handle is so held that the guide is disposed in the direction in which the train is moving and as the device is thrust downwardly the forks or arms of the guide will direct the device downwardly and center it over the rail. As the device is thrust downwardly the frame or yoke carrying the torpedo engages the tread face of the rail head and continued downward movement depresses the handle and causes the levers 5 to be swung outwardly towards the position shown in Figure 5. As the levers swing outwardly they act upon the arms 20 of the jaws 11 and cause the jaws to be swung downwardly and inwardly towards opposite sides of the rail and the straps will thus be bent against and under side portions of the head of the rail. The device is thrust downwardly quickly and with considerable force so that the jaws will be forced inwardly as soon as the yoke makes contact with the rail and the device is then drawn upwardly so that the spring can return the jaws and the levers to their normally retracted position and leave the torpedo applied to the rail. Since opposite side edges of the rail head engage inner side edges of the forks of the guide when the device is thrust downwardly to the position shown in Figure 5 the torpedo will be centered upon the tread of the rail in proper position to be exploded by a wheel of a train passing over it. A track walker or member of a train crew getting off of a train applies the torpedo in the same manner except that he stands upon the track instead of thrusting downwardly from the rear end of a moving train.

Having thus described the invention, what is claimed is:

1. A torpedo applying device comprising a handle, levers pivotally mounted at opposite sides of the lower end of said handle and extending down-

wardly therefrom, jaws having arms extending upwardly therefrom and each having a hinge member at the junction of its upper end with its companion arm, said arms being pivoted in spaced relation to their upper and lower ends to lower ends of said levers, a yoke for holding a torpedo disposed under said handle with said hinge members pivoted to its opposite side portions and mounting the jaws for swinging movement from an extended position downwardly towards each other for bending straps of a torpedo into gripping engagement with side portions of a rail head the free upper ends of the arms being flanged to engage the levers to limit the movement of the jaws, and a spring between said levers secured at its ends to the said arms and normally holding the levers and the jaws in a normal position.

2. A torpedo applying device comprising a handle, levers pivotally mounted for lateral swinging movement at opposite sides of the lower end of said handle and extending downwardly therefrom, jaws formed with arms extending upwardly therefrom and pivotally mounted intermediate their upper and lower ends to lower end of said levers the free ends of the arms engaging the levers to form stops, a yoke for holding a torpedo disposed under said handle and having opposite side portions engaged with the jaws at junction of the jaws with their arms to pivotally mount the jaws for swinging movement from an extended position downwardly toward each other to a torpedo-applying position, spring means normally holding said levers retracted and the jaws extended, and means for guiding the yoke to a position centered upon the tread surface of a rail head and holding a torpedo centered thereof as the jaws are moved towards opposite sides of the rail.

3. A torpedo applying device comprising a handle, a plate on the lower end of the handle projecting out from the sides of the handle, a shield below the plate, levers pivotally mounted at opposite sides of the plate for lateral swinging movement and normally extending downwardly therefrom, jaws having arms extending upwardly therefrom and pivotally mounted intermediate their upper and lower ends to lower ends of said levers, a yoke for holding a torpedo disposed under said handle and having opposite side portions engaged with the jaws at junction of the jaws with their arms to pivotally mount the jaws and their arms for swinging movement from a normal position to a torpedo-applying position, and a spring extending between said levers and anchored at its ends to lower ends of the levers to yieldably resist movement of the levers to an extended position.

4. A torpedo applying device comprising a handle, levers pivotally mounted at opposite sides of the lower end of said handle and extending downwardly therefrom, jaws having arms extending upwardly therefrom and pivotally mounted intermediate their upper and lower ends to lower ends of said levers, a yoke for holding a torpedo disposed under said handle and having opposite side portions engaged with the jaws at junction of the jaws with their arms to pivotally mount the jaws for swinging movement from an extended position downwardly toward each other to a torpedo-applying position, said yoke being of dimensions adapting it to have a torpedo passed upwardly through the same with straps of the torpedo projecting in opposite directions from the yoke and engaged with lower ends of the jaws, spring means yieldably resisting movement of the levers outwardly and normally holding the jaws extended,

and spring fingers for gripping the torpedo above the yoke and holding the torpedo in the yoke.

5. A torpedo applying device comprising a handle, levers pivotally mounted at the lower end of said handle and projecting downwardly from opposite sides thereof, jaws having arms projecting from their upper ends and hinge members at abutting ends of the jaws and their arms, tongues struck from said arms and rolled to form hinge sleeves spaced transversely from each other, pins 10 passing through said sleeves and through sleeves at lower ends of said levers to pivotally connect the arms with the levers, a yoke for carrying a torpedo disposed horizontally between lower ends

of said arms and having side portions passing through the hinge members to pivotally mount the jaws and their arms, and a spring extending between said levers with its ends anchored to portions of the pins between the hinge sleeves, said spring being extended as the handle is thrust downwardly to bring the yoke in engagement with a rail head and swing the levers outwardly to rock the levers upon side portions of the yoke and swing the jaws inwardly to a torpedo-applying position, and said spring when contracting returning the levers and the jaws to a normal position.
